UNITED STATES PATENT OFFICE.

CHARLES C. WRENSHALL, OF ST. PAUL, MINNESOTA.

TRACK-BOLT.

SPECIFICATION forming part of Letters Patent No. 355,112, dated December 28, 1886.

Application filed September 28, 1885. Serial No. 178,468. (No model.)

To all whom it may concern:

Be it known that I, CHARLES C. WREN-
SHALL, a citizen of the United States, residing
at St. Paul, in the county of Ramsey and State
5 of Minnesota, have invented certain new and
useful Improvements in Track-Bolts, of which
the following is a spe.-ification, to wit :

This invention relates to an improvement in
railroad-track bolts; and it consists in certain
10 peculiarities of the construction of the same,
substantially as will be hereinafter more fully
set forth and claimed.

In order to enable others skilled in the art
to which my invention pertains to make and
15 use the same, I will now proceed to describe
its construction and use, referring to the ac-
companying drawings, in which—

Figure 1 is a side view of my bolt. Figs. 2
and 3 are cross-sections of the same, and Fig.
20 4 is a view of the nut.

In the use of track-bolts on a railroad, the
greatest strain on the bolt is received from the
edge of the bolt-hole in the rail when the lat-
ter seeks to move in contraction from a change
25 of temperature, or from a continuous line of
rail, seeking to move with the trains, and
from which movements they are prevented by
the bolts of the splices to a large extent; so
the greatest strain is a longitudinal pull in line
30 with the track-rails, and bringing a cross or
shearing or bending strain on the middle of
the track-bolts. To strengthen the bolt against
this strain, and to enable it to withstand the
wear and tear of traffic, I prefer to construct
35 it as follows:

a represents the shank or main body of the
bolt, which is formed oval in cross-section, as
shown in the drawings, the longer diameter
when in use being always held horizontal to

counteract the extra strain in this direction. 40
The bolt is headed as usual, and the point
which projects beyond the joint-plate or fish-
plate is threaded for the reception of the nut.
This point is formed of a diameter somewhat
greater than the smaller diameter of the main 45
body or shank—that is, the amount of metal
removed from the longer diameter in round-
ing off the point for threading is added to the
smaller diameter, as fully seen in Figs. 1 and
3, and the strength of the bolt is thus retained 50
as great at the point as in the shank, and the
point is then threaded as usual. This effect
is readily gained by a single tap from the
“former” of a bolt-machine, and the diameter
is increased to such extent as to leave the 55
strength unimpaired by the cutting of the
thread. The bolt so formed, of oval cross sec-
tion, or with a longer horizontal diameter,
more effectually resists the strain of the track
contractions, and the increased thickness of 55
the point retains a uniform strength through-
out the article, leaving no points of especial
weakness to give way under the various strains
to which it is subjected.

Having thus fully described my invention, 65
what I claim as new, and desire to secure by
Letters Patent, is—

A track-bolt having a shank portion oval in
cross - section and an enlarged cylindrical
screw-threaded end of greater diameter than 70
the minor axis of the shank portion, as de-
scribed.

In testimony whereof I affix my signature
in presence of two witnesses.

CHARLES C. WRENSHALL.
